UNITED STATES PATENT OFFICE

PEDRO TORRABADELLA, OF CONCEPCION DEL URUGUAY, ARGENTINA

SYSTEM OF TELEVISION

Application filed January 21, 1927. Serial No. 162,617.

The present invention relates to a system of television and comprises a transmitting and receiving station.

The object of the invention is to simultaneously reproduce in the receiving apparatus changeable, movable or fixed images which are within range of the transmitting apparatus.

The invention is based on and consists of a combination of the known principles of telephotography, of the harmonic telegraphy and of the magnetizing of the polarized light, discovered by Faraday.

Referring to the accompanying drawing, Fig. 1 is the transmitting apparatus and Fig. 2 is the receiving apparatus.

The transmitting apparatus comprises a photographic camera B, the back of which is formed in the shape of a honeycomb having a plurality of cells C of any shape and conventional size. Each of the cells contains a portion of matter sensible to the variations of the intensity of the light which varies the current in the circuit in which they are inserted. This circuit is traversed by an intermittent current, the interruptions of which are produced by means of the prolonged vibrations of a diapason D, thus resulting in a determined and invariable tone or rhythm. The characteristic modulation resulting from a predetermined number of vibrations per second, the intensity of which is modified in the photoelectrogenous cellules C by effect of the changes of light, is printed by induction on a conductor by means of transformers having secondaries F and primaries E.

Each of the cellules forms part of a different circuit traversed by an electric current of different intensity; that is, the vibrating frequency of each diapason D is different so that a predetermined number of different vibrations is printed on a single conductor. These vibrations do not obstruct or interfere with one another, each of them carrying the variations of the light which forms the different dots of the analyzed image.

This compound modulation is amplified by

the amplifiers G and transmitted by an antenna.

The receiving apparatus shown in Fig. 2 comprises amplifiers J into which the wave is received from the sending antenna. Connected to the amplifiers is a microphonic relay K through which the modulations pass. The modulation is analyzed through primaries of a plurality of monotelephone bobbins M, the different vibrating tones of which correspond to the vibrating tones of the diapasons of the transmitter, thus reproducing in an equal number of circuits the same characteristics of each dot of the image analyzed in the transmitting apparatus.

Each of these circuits comprises a cellule O disposed on a plane in the place corresponding to the cellule of the transmitting apparatus to which it is analogous and which also vibrates in the same tone. These cellules of the receiving apparatus are each composed of two nicols, the axes of which are crossed, intercepting in this way the nicol which analyzes the light projected over the polarizing nicol. The electro-magnet is disposed between both nicols, and between its poles the pencil of rays of polarized light passes, and the latter passes through a substance active to said light. The pencil of rays moves around more or less following the variations of intensity of the current, allowing the passage of a larger or smaller quantity of light in each receiving cellule in proportion to the variations of light of each transmitting cellule.

The images that are in front of the transmitting apparatus are thus reproduced in the receiving apparatus, dot by dot with changes of position and luminosity simultaneously in both apparatus.

In accordance with all that is expressed and described I claim as of my exclusive property and rights:—

A system of television comprising a transmitting and receiving apparatus, said transmitting apparatus comprising a light sensitive cell having a plurality of cells sensible to the different variations of the intensity of light and adapted to be varied by the passage of light through images brought in its vicinity.

ity, each of said cells being connected in circuit with the primary of a transformer, a tuning fork having a predetermined frequency and a source of supply, each of said 5 transformers having their secondaries connected in zones with an amplifier, an antenna connected to said amplifier, whereby upon the change of intensity of light upon said light sensitive cells, the different vibrations 10 of the tuning forks inducing different impulses into the secondaries of said transformers, said receiving apparatus comprising an amplifier connected to an antenna for receiving the waves from said transmitting apparatus, a relay in circuit with said amplifier, a plurality of tuned reeds having frequencies corresponding to the frequencies of the tuning forks in said transmitting apparatus connected in circuit with said relay, through a corresponding number of 15 transformers, and a source of supply, each of said reeds being connected to corresponding light cells in a light sensitive cell, a source of light, and a reproducing screen, 20 said light being adapted to cast light rays through said cell whereby the picture transmitted is reproduced on said screen dot by dot with the same position and luminosity.

25 In testimony whereof I affix my signature.
20 PEDRO TORREABADELLA.
